UNITED STATES PATENT OFFICE.

HORACE C. STARR AND WILLIAM C. VANNEMAN, OF RICHMOND, INDIANA.

GRAIN-DRILL.

SPECIFICATION forming part of Letters Patent No. 271,533, dated January 30, 1883.

Application filed September 25, 1882. (No model.)

To all whom it may concern:

Be it known that we, HORACE C. STARR and Wm. C. VANNEMAN, citizens of the United States, residing at Richmond, in the county of Wayne and State of Indiana, have invented 5 certain new and useful Improvements in Grain-Drills, of which the following is a specification, reference being had therein to the accompanying drawings.

Our invention consists in improvements in that class of grain-drills in which the hoes are held in their normal position by means of a spring; and the object of the invention is to allow the hoe of a grain-drill to encounter obstructions in the ground and pass over them without the danger of breaking the hoes or otherwise injuring the drill. To accomplish this result the hoes are arranged so as not to leave their proper or working position unless 15 the obstruction encountered offers enough resistance to endanger the hoe. When this resistance reaches a certain point the hoe revolves backward, passing over the obstruction, and is returned to its original position by means 20 of a spring and certain connections.

The invention consists, in connection with a hoe for a grain-drill, first, in a rocking cylinder, having an arm, and hooks cast in one piece, and arranged to revolve on a shaft, between the 25 drag-bars.

It also consists of a double spring having a central loop for securing it to the hooks on the rocking cylinder, around which it is wound on each side, while its ends are bent and held under said drag-bars.

It also consists in a double curved connecting bar or arm attached at one end to the arm on the rocking cylinder, while the other end is attached to a hook or lug on the hoe.

It further consists in arranging extra hooks on the rocking cylinder, by which the tension of the spring, when weakened by use, can be readjusted; and it also consists in certain details of construction and arrangement of certain parts, as will be more fully described hereinafter, and more specifically pointed out in the claims, reference being had to the accompanying drawings and the letters of reference marked thereon.

Like letters of reference refer to similar parts

in the different figures of the drawings, in which—

Figure 1 represents a plan or top view of the drag-bars and hoe in position. Fig. 2 is a side elevation of the same. Fig. 3 is a sectional view of the rocking cylinder and adjacent parts. Fig. 4 is a modification of the manner of attaching the curved connecting-arm.

In the drawings, A represents the drag-bars or hoe-beam, consisting of two bars bent or curved at the rear end, so as to clasp an ear or lug on the hoe B. The front ends of the bars are held apart by a bolt and thimble and the sides of a rocking cylinder. The ear or lug G is provided with a series of holes or perforations, a, arranged in the arc of a circle, to adjust the hoe in different positions or inclinations by a bolt passed through the holes. Near the bent part of said bars is pivoted or axially journaled on studs e a rocking cylinder, E, 65 having at its rear side a series of hooks, J, centrally arranged, on which the central part of a spring, I, formed into a loop, is attached, while the outer ends thereof are bent outward and held under the drag-bars A. The spring is 70 coiled around the cylinder E, and the tension thereof can be adjusted by a tension-screw, F, by which means also the point K of the curved connecting arm or lever C may be thrown in and out of line with the points H and L. By 75 this means the resistance required at the breaking or starting point of the hoe is regulated.

The curved connecting-arm C is made double or U-shaped, and provided at its opposite ends with a transverse pin, and is attached at one 80 end to the hook on the end of the arm D, cast on the rocking cylinder E, while the other end is attached to a hook, b, on the hoe B.

The arm D may be provided with an eye, d, at one end, with a hole, e, in it, if desired, in- 85 stead of a hook, so that a bolt or rivet may be employed to make the joint, and a similar joint may be employed to connect the curved arm C to a lug, g, on the hoe with its opposite end, as shown in Fig. 4.

For adjusting the pitch or inclination of the hoe B to a greater or less angle a series of holes, a, are arranged in the ear G, in the arc of a circle, into which holes a bolt is entered, passing through the ends of the drag-bars A, 90

and according to the hole in which they are secured the inclination of the hoe is changed. The tension-screw F is set in a plane and at right angles to the arm D, and passes into the cylinder E, which is made solid, and this forms an important feature of this invention. Additional hooks J, to tighten the spring when weakened by use, may be applied to cylinder E, over which the center loop of the spring I 10 may be slipped.

The advantages of this improved construction of hoe for grain-drills will be readily appreciated by those skilled in the art, and some of them are that the tension of the spring can 15 be adjusted as required in an expeditious manner, and the resistance of the hoe desired at the point of breaking or starting can be regulated to a nicety. The device is much simpler in its construction than any now in use, as but 20 four pieces are required—viz., one spring, a tension-screw, one rocking cylinder, and a curved connecting-arm. The pitch or inclination of the hoe can be quickly regulated as desired, and the device is not liable to get 25 out of order, and it can be furnished at a very moderate cost.

Having thus described our invention, what we claim, and desire to secure by Letters Patent, is—

30 1. In a hoe for grain-drills, a cylinder, E, having an arm, D, journaling-studs e, and a series of hooks, J, cast in one piece, substantially as specified.

2. In a hoe for grain-drills, an adjusting-screw, F, in combination with a rocking cylinder, E, having an arm, D, studs e, and a series of hooks, J, substantially as and for the purpose set forth.

3. In a hoe for grain-drills, a double spring, I, having a central loop for adjusting it on the hooks J of the rocking cylinder E, substantially as herein specified.

4. In a hoe for grain-drills, the adjusting-screw F, passing into the rocking cylinder E, provided with an arm, D, and a series of hooks, J, in combination with a double spring, I, having central loop, substantially as described.

5. The combination of a rocking cylinder, E, having an arm, D, and a series of hooks, J, with a double spring, I, a curved connecting-arm, C, and a hoe, B, all arranged substantially as and for the purpose specified.

6. The combination of the drag-bars A, rocking cylinder E, having arm D, a series of hooks, J, and a tension-screw, F, with a double spring, I, provided with a central loop, a curved connecting-arm, C, and a hoe, B, with adjusting-holes a, all arranged substantially as shown and specified.

In testimony whereof we affix our signatures 60 in presence of two witnesses.

HORACE C. STARR.

WILLIAM C. VANNEMAN.
